REFRIGERATING APPARATUS

Richard E. Gould, Dayton, Ohio, assignor to General Motors Corporation, Dayton, Ohio, a corporation of Delaware

Application October 31, 1934, Serial No. 750,849

13 Claims. (Cl. 62—6)

This invention relates to refrigeration.

It is an object of this invention to provide an improved refrigerating apparatus which is particularly useful in cooling rooms or other enclosures.

Further objects and advantages of the present invention will be apparent from the following description, reference being had to the accompanying drawing, wherein a preferred form of 10 the present invention is clearly shown.

In the drawing:

The figure is a vertical cross-sectional view, somewhat diagrammatic, of an apparatus embodying features of my invention.

15 A refrigerating apparatus, in accordance with my invention, includes, in general, a refrigerant translating device, such as a compressor 10, driven by a motor 11, in refrigerant flow relationship with an evaporator 12 and a condenser 13. The translating device and the evaporator preferably are mounted on a cabinet 14, which is adapted to be placed in the room 15, the air for which is to be cooled or conditioned. The condenser 13 is adapted to be mounted outside of the room, and 20 the arrangement is such that the heat which is absorbed by the refrigerating apparatus from the air to be conditioned is discharged into the atmosphere outside of the room through the condenser 13.

25 30 A certain amount of heat is generated by the refrigerant translating device, and it is desirable to prevent this heat from being transmitted to the room 15. To this end, the translating device is housed in an insulated enclosure 16, which, for example, may be located in the lower part of the cabinet 14. The evaporator 12 may be located in the upper part of the cabinet 14. Air for the room 15 may be circulated thereover by means of a fan 17 driven by a motor 18, the air entering 35 at inlet 19 and being discharged at the outlet 20. The air entering at 19 may come from the room 15 as shown, or may come from outside the room, or both from inside and outside the room, if desired.

40 45 Means are provided for evaporating high pressure liquid refrigerant in thermal exchange with the translating device and for condensing the vaporized refrigerant thus formed for reuse. Preferably this refrigerant is the same refrigerant which is circulated through the translating device, evaporator and condenser. In order to accomplish this, the refrigerant which is evaporated in the evaporator 12 flows through the vapor line 21 to the compressor 10 where it is compressed and is discharged through the line 22 to

the condenser 13. The liquefied refrigerant from the condenser 13 flows through the line 23 to a liquid refrigerant receiver 24, from whence the refrigerant may flow through the line 25 to an expansion valve 26 leading to the evaporator 12. 5 The valve 26 may be of any automatic type, and preferably is of the type which introduces liquid refrigerant into the evaporator whenever the pressure therein is reduced below a predetermined limit. The valve 26 is preferably also provided with a thermostatic bulb 27 which throttles the valve 26 whenever the refrigerating effect in the evaporator reaches the bulb 27.

10 A portion of the high side liquid refrigerant is evaporated in thermal exchange with the translating device, preferably in the exchanger 28. A pump 29, which is preferably actuated by the flow of refrigerant, is provided. This pump may take the form of a jet, or venturi, pump placed in the discharge line 22, with its suction 15 connection 30 connected to the heat exchanger 28. When the compressor 10 operates, the flow of refrigerant through the venturi 29 reduces slightly the pressure in the connection 30 and thus withdraws any vaporized refrigerant from the exchanger 28 where a portion of the liquid refrigerant is evaporated by the heat of the compressor 10 and/or motor 11. The vapor thus formed finds its way into the line 22 and is formed 20 to be condensed in the condenser 13. 30

25 The exchanger 28 may be of any suitable construction which permits liquid refrigerant to rise therein. Thus it may be formed of a plurality of tubes connected to the cylindrical receiver 24 in header-like formation and their upper ends may 35 be connected to a header 31 which in turn is joined to the connection 30. The tubes may be provided with fins 32. The level of the liquid in receiver 29 is such that liquid is maintained in the tubes of exchanger 28. 40

30 35 When the refrigerating system is to be used to cool a room or the like, the cabinet 14 may be placed inside of the room, while the condenser 13 may be supported outside of the room by means of brackets 33 which are vertically adjustably secured to the cabinet at 34 and which pass through the window just above the sill 35. A false sill 36, made of rubber or the like, surrounds the brackets 33 and thus permits a substantially tight joint between the sash 37 and the false sill 36. 45

40 45 Means are provided for discharging the moisture condensed on the evaporator 12 outside the room. To this end, a drain pan 38 is placed underneath the evaporator 12. A pipe 39 is connected to a pump 40 to withdraw the moisture 50 55

from the pan 38 and to discharge it at the spray-head 41 over the condenser 13 where it is vaporized. The pump 40 may be operated by motor 42 which conveniently may also operate the fan 43 which circulates air over the condenser 13 through the openings 44 and 45, carrying with it the vaporized moisture.

Controls for the motors may be provided. Thus a hand switch 46 causes the motor 18 to operate whenever the switch is closed. A thermostatic switch 47, in series with another hand switch 46', causes the motors 11 and 42 to operate whenever it is closed and while the switches 46 and 46' are closed. The thermostatic switch 47 may be made responsive to conditions created by the apparatus and the thermostatic bulb 48 thereof may be conveniently placed near the opening 19 to be effected by the air from the room 15. The bulb 48 may be a dry bulb, a wet bulb or a combination of both thus to be responsive in part or in whole to the irrelative humidity within the room and/or to its temperature. By this arrangement the motor 18 may be operated even when refrigeration is not required, and its operation is made necessary when refrigeration is required.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising a refrigerant translating device, a condenser and an evaporator in refrigerant flow relationship, and means for evaporating high pressure liquid refrigerant in thermal exchange with said translating device and for condensing the vaporized refrigerant thus formed, said means including a pump operated by the flow of refrigerant.

2. Refrigerating apparatus comprising a refrigerant translating device, a condenser and an evaporator in refrigerant flow relationship, and means for evaporating high pressure liquid refrigerant in thermal exchange with said translating device and for condensing the vaporized refrigerant thus formed, said means including a jet pump.

3. Refrigerating apparatus comprising a compressor, condenser and evaporator in refrigerant flow relationship, a motor drivingly connected to said compressor, and a pump operated by refrigerant flowing through said compressor for circulating liquid refrigerant to cool said motor.

4. Refrigerating apparatus comprising a compressor, condenser and evaporator in refrigerant flow relationship, a motor drivingly connected to said compressor, and a pump operated by refrigerant flowing through said compressor for circulating liquid refrigerant to cool said compressor.

5. In a cooler for a room or the like, a cabinet, an evaporator and a refrigerant translating device mounted therein, bracket means mounted on the cabinet and having a free end adapted to extend through a window and a condenser mounted on the free end of the bracket means, refrigerant flow means between said evaporator, translating device and condenser, a blower for circulating air over said condenser, a control responsive to air conditions in said room and controlling the operation of said translating device and blower, and means for evaporating high pressure liquid refrigerant in thermal exchange with said translating device and for condensing the vapor thus formed outside said window.

6. In a cooler for a room or the like, a cabinet, an evaporator and a refrigerant translating device mounted therein, bracket means mounted on the cabinet and having a free end adapted to extend through a window and a condenser mounted on the free end of the bracket means, refrigerant flow means between said evaporator, translating device and condenser, a blower for circulating air over said condenser, a control responsive to air conditions in said room and controlling the operation of said translating device and blower, means for evaporating high pressure liquid refrigerant in thermal exchange with said translating device and for condensing the vapor thus formed outside said window, and means for discharging water condensed on said evaporator outside said window.

7. In a cooler for a room or the like, a cabinet, an evaporator and a refrigerant translating device mounted therein, bracket means mounted on the cabinet and having a free end adapted to extend through a window and a condenser mounted on the free end of the bracket means, refrigerant flow means between said evaporator, translating device and condenser, a blower for circulating air over said condenser, means for evaporating high pressure liquid refrigerant in thermal exchange with said translating device and for condensing the vapor thus formed outside said window, and means for discharging water condensed on said evaporator outside said window.

8. In combination, a refrigerant translating device, a condenser and an evaporator in refrigerant flow relationship, a heat exchanger in thermal exchange with said translating device, means for supplying liquid refrigerant to said heat exchanger, and a jet pump operated by refrigerant flowing through said translating device for reducing the pressure in said heat exchanger.

9. In combination, a low side evaporator, a translator, a condenser and a high side liquid receiver in refrigerant flow relationship, a jet pump with the inlet of the jet connected to the translator, the outlet of the pump connected to the condenser and the suction inlet of the pump connected to the receiver.

10. Refrigerating apparatus comprising a compressor, condenser and evaporator in refrigerant flow relationship, and means for dissipating heat of compression comprising an evaporator and a jet pump operating by refrigerant discharged by said compressor for evaporating a portion of the liquid refrigerant.

11. Refrigerating apparatus for a room or the like comprising a compressor and an evaporator mounted within the room and a condenser mounted without the room, refrigerant flow connections between said compressor, evaporator and condenser, and a jet pump operated by refrigerant discharged by said compressor for evaporating a portion of the liquid refrigerant.

12. Heat exchange apparatus of the character described comprising a refrigerating mechanism inclusive of evaporator and condenser units, means for the circulation of air to be cooled about the evaporator unit, means for the circulation of cooling air about the condenser unit, means for collecting condensate from the evaporator unit and forcibly spraying it into the path of the air circulated about the condenser unit, and means for evaporating liquid refrigerant in thermal exchange with a portion of said refrigerating mechanism, said last named means in-

cluding a pump operated by the flow of refrigerant.

13. Refrigerating apparatus comprising a refrigerant translating device, a condenser and an evaporator in refrigerant flow relationship, and means for diverting a portion of the high pres-

sure liquid refrigerant from said condenser into thermal exchange relationship with said translating device to be vaporized thereby and for returning such vaporized refrigerant to said condenser, said means including a pump.
